CLAIM

The ornamental design for a combined bird feeder shield and perch, as shown and described.

DESCRIPTION

FIG. 1 is a front perspective view of a combined bird feeder shield and perch showing my new design;
FIG. 2 is a front elevational view thereof;
FIG. 3 is a rear elevational view thereof;
FIG. 4 is a right side elevational view thereof, the left side being a mirror image of the right side shown; and
FIG. 5 is a top plan view thereof, the bottom being a mirror image of the top shown.

FIG.1

FIG. 2

FIG. 3

FIG. 4

FIG. 5
